[57] ABSTRACT

A waste compactor for compacting waste in a container comprises a ram which reciprocates into and out of the container to compress the waste. The ram is preferably box-like and has a bottom opening which is normally closed by doors or flaps. Waste material can be fed into the compactor at a level above the opening and, when the doors are opened, preferably automatically during the ram stroke, the waste passes through the opening to the container, the doors being closed before the ram compresses the waste material.

FIG. II.

WASTE COMPACTORS

This invention relates to waste compactors of the form comprising a ram and a drive arrangement operable to reciprocate the ram into and out of a container to compress waste material therein.

In known compactors of this general form the ram is moved upwardly out of the container when it is desired to insert waste material and the waste material is fed into the container through an opening below the level of the raised ram. The opening is normally closed by a door which when opened cuts out all operations of the waste compactor, but there is a possibility that, due to a fault, the ram could move downwardly while waste is being inserted in the container and crush the hand or arm of the person inserting the waste. Furthermore, while the ram is raised to insert waste material, air can circulate around the waste and out of the opening carrying with it any unpleasant odours.

The present invention overcomes these disadvantages of the known compactors and provides a waste compactor in which waste material can be fed into the container through an opening above the level of the ram.

In accordance with the invention there is provided a waste compactor comprising a ram and a drive arrangement operable to reciprocate the ram into and out of a container to compress waste material therein, characterized in that the ram has a bottom opening to permit waste material inserted in the compactor at a level above the opening to pass through the ram into the container, and that the ram has a closure assembly which closes the opening before the ram compresses the waste material in the container.

Preferably, the closure assembly comprises one or more doors or flaps which are opened automatically towards the end of the upward stroke of the ram by respective door-operating mechanisms.

In one form of waste compactor described in more detail below, the cycle of the ram is controlled by ram-operated micro-switches located in or near the working area of the ram. While this is acceptable for some waste compactors, in an alternative form of compactor the micro-switches and their electrical connections are remote from the working area of the ram. In this alternative form, the micro-switches are easier to reach for repair or service and the problems of insulation are not so great since the micro-switches do not come into contact with moisture from the waste material.

In the alternative form of the compactor according to the present invention, a ram position indicating device is mounted remote from the ram and comprises a further feed screw drivingly coupled to the drive feed screws and carrying a nut member held against rotation, movements of the nut member along the further feed screw representing on a reduced scale movements of the ram along the drive feed screws. The micro-switches are mounted for engagement by the nut member to control the motor. Thus, the micro-switches and their electrical connections are remote from the working area of the ram.

One form of waste compactor in accordance with the invention will now be described, by way of example, with reference to the accompanying drawings, in which:

FIG. 1 is a perspective view of the waste compactor,

FIG. 2 is a side view of the waste compactor with the housing removed, and showing a ram in its retracted position,

FIG. 3 is a plan view of the waste compactor with the housing removed,

FIG. 4 is an enlarged view of a mechanism for operating flaps or doors of the ram,

FIG. 5 is an enlarged part-sectional view of a load sensing device of the waste compactor, and

FIG. 6 is an enlarged view of part of the waste compactor and a waste container supported therein,

FIG. 7 is a sectional view of part of the ram showing part of a modified form of door operating mechanisms,

FIG. 8 is a section taken along line B—B of FIG. 7,

FIG. 9 is a part-sectional view of a further modification showing a ram position indicating device,

FIG. 10 is a plan view of the device of FIG. 9, and

FIG. 11 is an enlarged view of a modified door of the waste compactor.

The waste compactor comprises a frame for a sheet metal housing 1 which houses a ram 2 and a removable container 3. The ram 2 is a box-like structure and is supported by three generally equiangularly spaced drive feed screws 4 each of which is rotatably mounted in thrust bearings 5 and carries ram frame members 8 comprising a captive nut 6. A reversible motor 9 has a pulley 11 connected to its drive shaft and drivingly coupled by an endless toothed drive belt 13 to a pulley 12 fast with one of the screws 4. The drive is transmitted to the other screws 4 by a further endless toothed belt 14 passing around three pulleys 15 mounted on the respective screws 4.

A hinged door 16 can be opened for the insertion of waste into the compactor above the ram 2 so that there is no possibility of the ram crushing the fingers or arm of the user when waste is inserted.

Flaps or doors 17 are provided at the bottom of the ram 2 to allow the waste to pass through into the container 3. The doors 17 are arranged to open automatically as the ram 2 approaches the end of its upward stroke by respective door operating mechanisms 18 shown clearly in FIG. 4, each of which comprises a rod 19 passing through apertured guide members 20 attached to the frame of the ram 2 and screw threadedly connected at its lower end to a lug 21 which is pivotally connected to a lever 22. Each door is pivotable about a hinge 23 along one edge, the lever 22 being pivotally connected to the door adjacent said edge and centrally thereof. A compression coil spring 24 surrounds the rod and is arranged to act between the lower guide member 20 and an abutment member 25 connected, for example by a pin 26, to the rod 19.

As the ram approaches the end of its upward stroke, each rod 19 abuts a fixed frame member 27 of the compactor and moves downwardly, relative to the ram 2, against the action of the spring 24 to the position shown in chain lines in FIG. 4. This movement causes corresponding movement of each lever 22 to open the doors 17.

When the ram starts its downward stroke the force of springs 24 keeps the rods 19 in abutting engagement with the frame members 27, and the rods therefore move upwardly relative to the ram 2 and the doors close.

To operate the compactor the electrical supply is switched on and is indicated by an indicating lamp 10 and a start button 28 on the housing is actuated to start

the motor 9 to bring the ram 2 to its starting position, i.e. to the end of its downward stroke.

The electrical circuitry forms no part of the present invention and need not be described in this specification.

Waste can now be inserted into the compactor through the waste door 16 which operates a micro-switch 29 as it opens to cut out all mechanical functions and prevent the ram moving while there is a possibility of a hand being inserted through the opening. The waste falls into the ram 2 through a guide chute 30 and the door 16 is closed to actuate the micro-switch 29 and operate the motor 9 and rotate the screws 4 in a direction (clockwise as seen in FIG. 3) to move the ram upwardly. As the ram approaches the end of its stroke the doors 17 automatically open, as previously described, and the waste falls into the container 3. At the end of its upward stroke the ram 2 actuates a micro-switch 31 at the top of the compactor to reverse the motor 9 and start the ram on its downward stroke. The ram doors 17 then close automatically, as previously described. The ram moves into the container 3 and compacts the waste in the container until a predetermined force, for example 2 tons, is reached at which time a load sensing device 32 (to be hereinafter described) associated with the drive belt 13 operates a micro-switch 33 to stop the motor. On stopping of the motor the ram pressure is released slightly owing to any lost motion in the drive mechanism and the natural resilience of the parts of the mechanism. Thus the ram is disposed within the container in the inoperative position.

The load sensing device 32 (shown clearly in FIG. 5) comprises a lever 34 pivoted at its outer end to a fixed pivot pin 35 and carrying at its inner end a roller 36 which is held in engagement with a run 37 of the drive belt 13 by a tension spring 38 connected between the inner end of the lever 34 and a mounting hook 39 which is adjustably connected to a fixed bracket of the compactor frame 1. When the ram is moving downwardly, the motor pulley 11 and screw pulley 12 are rotating anti-clockwise as seen in FIG. 3 so that the run 37 of the belt 13 is under tension. In operation, as the load is applied to the waste by the ram, rotation of the drive screw 4 and thus pulley 12 is slowed down while the motor pulley 11 is tending to rotate at its normal operating speed. Thus the tension in the run 37 of the belt 13 increases and the roller 36 and lever 34 are moved against the force of the spring 38. Upon a predetermined movement of the lever 34, it actuates the micro-switch 33 to switch off the motor 9. The spring force of spring 34 required to allow a desired maximum ram force can, of course, be calculated.

A micro-switch 41 which controls a warning lamp 40 is provided which, in normal downward movement of the ram, is actuated thereby to prevent the lamp 40 being switched on. If, however, the ram does not move a sufficient distance downwardly to actuate the micro-switch 41, i.e. when the container 3 is full of waste, then when the predetermined load is reached and the motor 9 is switched off, the micro-switch 41 actuates the warning lamp to show that the container is full.

To empty the waste, an unload button 42 is actuated to operate the motor and cause the ram to move upwardly out of the container. When the ram 2 is raised the motor 9 is automatically switched off and the container 3 can be removed from the compactor. The container has wheels 43 to permit easy removal from the

compactor and easy conveyance to a waste collection point. Preferably the container is lined with a bag for example of polythene, which can be removed and tied so that the waste is in an easily disposable form. After removal of the waste a fresh bag is inserted in the container which is replaced in the compactor. A micro-switch 44 is provided inside the compactor on the wall remote from the opening from the container, which is actuated when the container is fully inserted in the compactor. The micro-switch 44 controls the electrical power supply such that if the container is not in place in the compactor the ram will not operate.

As can be clearly seen in FIG. 6, rubber blocks 45 are mounted between respective wheels 43 and the container 3, the blocks 45 being incompressible until a predetermined load, say 80 lbs, which is greater than the weight of a fully laden container, is applied thereto. When a load greater than 80 lbs is applied, i.e. when the ram is exerting a load, the blocks 45 are compressed and the container drops on to a fixed support member 46 which is connected to and supported by mild steel packing blocks 47 on the compactor frame. Thus when the ram is not exerting a load the weight of the container and waste is taken by the wheels 43 and the container is just clear of the support member 46 so that the container can easily be moved into and out of the compactor, and when the ram exerts a load it is transferred to the compactor frame through the packing blocks 47.

FIGS. 7 and 8 illustrate an alternative form of door-operating mechanism which is located adjacent the hinged edge of its associated ram and at the back of the ram instead of at the side of the ram centrally of each of the doors as in the above-described embodiment. The mechanism has a rod 19a supported in upper and lower guide members 20a attached to the frame of the ram 2. A coil compression spring 24a acts between the lower guide member 20a and an abutment member 25a secured to the rod 19a by a pin 26a. The rod 19a is connected at its lower end to a slide member 51 extending through and guided in a slot 52 in one side of the ram 2, the slide member 51 having a pivotal connection with the upper end of a link 22a, the lower end of which is pivotally connected to a lug 53 welded to the door 17a which is mounted on a pivot shaft 23 for rotation about the shaft axis. The link and slot 52 are enclosed by a cover 55 to prevent waste clogging the mechanism, the cover preferably extending the length of the ram so that there are no shelves on which waste can collect.

Operation of the door-operating mechanism is generally similar to that previously described. Briefly, near the end of the upward ram stroke the rod 19a engages a fixed frame member and moves downwardly relative to the ram against the bias of spring 24a, the slide member 51 moving downwardly in the slot 52 with link 22a to pivot the doors 17a about their shafts 23 anti-clockwise and clockwise, respectively, as seen in FIG. 7. Downward movement of the ram effects closure of the doors.

FIGS. 9 and 10 show a modification which permits the ram-operated micro-switches and the associated electrical apparatus to be disposed remote from the working area of the ram, in this instance above the ram. A slave screw 61 is drivingly coupled to the drive feed screws by non-rotatably mounting the slave screw on the pulley 5 of one of the drive feed screws 4. The slave screw carries a nut member 62 having a longitudinal

slot 63 (FIG. 10) which receives an edge of a fixed plate 64 supporting micro-switches 65, 66, 67. Movement of the nut along the slave screw corresponds to and represents movement of the ram in its feed screws 4, but on a reduced scale. The scale reduction in this case is achieved by providing the slave screw 61 with a lead less than the lead of the feed screws 4, the ratio of the leads determining the ratio of the movements of the nut member 62 and the ram 2. The scale reduction could be achieved in some other way, for example by introducing reduction gearing between the drive feed screws 4 and the slave screw 61.

Thus, when the ram 2 moves through its cycle, the nut member 62 moves correspondingly along the slave screw and operates the micro-switches 65-67. The upper micro-switch 65 corresponds to the switch 31 previously described and is actuated at the end of the upward stroke to reverse the motor 9 and the micro-switch 66 corresponds to the previously described switch 41 to indicate when the container is full. The lower switch 67 is operated when the ram reaches the end of its downward stroke.

It will be appreciated that the switches 65-67 can be smaller and less robust than their counterparts in the previously described embodiment and are therefore cheaper. Furthermore, the micro-switches and all their electrical connections are away from the working area of the ram to reduce any risk of accident or damage and to make servicing or repair of the electrical system much easier and reduce problems of insulation. The motor 9 is conveniently also mounted above the ram working area, so that all the electrical connections are clear of the ram working area, which may be washed out or hosed down without damaging the electrical circuitry. However, it will be appreciated that the motor can be mounted in any desired position with suitable modification to the drive transmission.

FIG. 11 illustrates a modification to the door 16. The modified door carries at its lower end two rollers 71, one on each side, movable along respective fixed guide tracks 72 extending inwardly and downwardly. A link 73 is pivotally connected at one end to the door 16 at a point 74 intermediate the upper and lower ends of the door and at the other end at 75 to a fixed member 76. The door 16 is shown in its closed position in full lines and is opened by pulling a handle at the upper end of the door so that the rollers slide along their guides, the pivot points 74 travelling through an arc of a circle whose centre is pivot point 75, until the door is in its partially open position shown in chain dotted lines. Further pulling of the handle moves the door to its fully open position shown in chain dotted lines in which the door acts also as a chute for waste material fed into the opening. The extent to which this door moves out from the compactor during opening is limited by the length of the link 73 and is less than that of the previously described door. With this modification the user does not have to move backwards to avoid the door when opening it.

It will be appreciated that the use of three drive screws ensures that a substantially even load is applied to the waste across the whole area of the ram.

It will be apparent to those skilled in the art that modifications of the above described waste compactor are possible within the scope of the invention. For example, the mechanism 18 for controlling the ram doors may be disposed with. The doors may be freely hinged to open under the action of gravity and to close when

they come in contact with the waste in the container on the downward stroke of the ram. The doors would then preferably be suitably shaped to avoid digging into the waste on the downward stroke.

5 Further, a different load sensing device could be used instead of the above described device.

I claim:

1. A waste compactor for compacting waste material in a container, comprising a housing; a waste-receiving container located within the housing and being removable therefrom; a ram mounted for reciprocal movement within the housing and cooperating with the container to compact waste material emptied into the compactor into said container; drive means for reciprocating the ram between a retracted position and a compressed position where it compresses waste material into the container, said ram having an opening therethrough; closure means for closing said ram opening; and control means for opening said closure means when the ram moves in a direction toward its retracted position and for closing said closure means when the ram moves in a direction toward its compressed position, said control means keeping the ram in its compressed position against previously compressed waste while additional waste material is being emptied into the compactor at a level above said ram and upon selective actuation reciprocating said ram toward its retracted position to open the closure means and permit the collected waste material to pass through said opening into said container and to thereafter reverse the direction of the ram to compress the wasted material that has passed through the ram into said container and to again hold the compressed waste in compression while additional waste is emptied into the compactor.

35 2. A waste compactor according to claim 1 wherein said closure means comprises at least one door pivotally attached to said ram, and said control means comprises at least one door-operating means operative to open the door automatically as said ram approaches its retracted position and to close the door automatically during its compression stroke.

3. A waste compactor according to claim 2, wherein said door-operating means comprises an operating rod movable with said ram, a linkage pivotally connecting said associated door to said operating rod, and a stop engageable by said rod towards the end of said upward stroke of said ram to permit movement of said ram relative to said operating rod and effect pivotal movement of said door to open it.

4. A waste compactor according to claim 1, wherein said drive means comprises a plurality of spaced-apart parallel drive feed screws rotatably mounted in said compactor, ram frame members supported respectively by said drive feed screws, and movable therealong, drive transmitting means, and a drive motor drivingly coupled through said drive transmitting means to said drive feed screws.

5. A waste compactor according to claim 4, wherein said drive transmitting means comprises a toothed belt and pulley system.

6. A waste compactor according to claim 5, wherein said belt and pulley system comprises two pulleys, one connected to said drive motor and the other to one of said drive feed screws, and a drive belt extending around said pulleys to transfer the drive from said motor to said drive feed screw, and further comprising load sensing means for sensing a predetermined load of said ram on said waste material, said load sensing

means comprising a lever mounted for pivotal movement about a fixed axis, roller means carried by said lever, spring means biasing said roller into engagement with one run of said drive belt and switch means operable by said lever, said lever being movable towards said switch against said bias of said spring means as the tension in said belt run increases due to said ram compacting said waste material, whereby said switch is actuated when said lever moves through a predetermined distance corresponding to said predetermined load.

7. A waste compactor according to claim 4, further comprising ram position indicating means including a further feed screw rotatably mounted remote from said ram and drivingly coupled to said drive feed screws, a nut member carried by said further feed screw and movable therealong, movement of said nut member along said further feed screw representing on a reduced scale movements of said ram along said drive feed screws, and at least one switch means mounted for en-

gagement by said nut member to control said drive motor.

8. A waste compactor according to claim 1, wherein said drive means reciprocates said ram to a compressed position near the bottom of said container and to a retracted position outside of said container.

9. A waste compactor for compacting waste material in a container, comprising a ram, drive means operable to reciprocate said ram into and out of said container to compress the waste material therein, and ram position indicating means located remote from said ram, and comprising a feed screw mounted for rotation, a nut member carried by said feed screw and means holding said nut member against rotation said feed screw being coupled to said drive means whereby movement of said nut member along said feed screw represents on a reduced scale movement of said ram in response to operation of said drive means.
